BRAILLE TYPEWRITING MACHINE

Erik Frey and Samuel A. Cooper, Chicago, Ill.

Application March 17, 1951, Serial No. 216,178

9 Claims. (Cl. 197—6.1)

1

This invention relates to a Braille typewriter adapter and concerns itself with a machine having the usual six impression bars each of which is actuated by a solenoid energized by a circuit established by the operation of a typewriter key on an ordinary typewriter.

It is an object of this invention to increase the range of key actuated mechanism for causing the energization of the Braille printing solenoids; or, in other words, to increase the actuating symbols over those usually found upon the standard typewriter.

It is a further object of this invention to simplify the Braille typing machine and render the same easily adaptable for use with existing typewriters, or to typewriters slightly modified to increase the actuating symbols on the operated keys.

It is a further object of this invention to provide an improved system of Braille printing or typing.

In order that our invention may be more fully disclosed, reference is had to the accompanying drawings, which illustrate an improved Braille typewriting apparatus embodying the foregoing and such other principles, advantages or capabilities as may be pointed out as this description proceeds, or as are inherent in the present invention. For purposes of clarity in exposition, the following description is explicit, and the accompanying drawings are detailed, but it is distinctly to be understood that said exposition is illustrative only, and that our invention is not restricted to the particular details recited in the specification or shown in the drawings.

In the drawings:

Fig. 1 is a plan view of a Braille writer connected to a typewriter and actuated through an adaptor unit positioned beneath said typewriter;

Fig. 2 is a diagrammatic view with parts of the typewriter and adaptor unit in section;

Fig. 3 is a plan view of certain encoded bars and associated switches, normally mounted in or below the typewriter, with certain other parts removed;

Fig. 4 is a fragmentary perspective view of the encoded bars and other parts shown in Figure 3;

Fig. 5 is an enlarged, detail, diagrammatic view of the six encoded bars illustrating the key voiding notches and their relation to the adaptor unit;

Fig. 6 is an enlarged plan view of the typewriter keys as visualized by the blind person and which keys coact with the encoded bars;

Fig. 7 is a sectional view taken upon the line 55

2

7—7 of Fig. 1 looking in the direction of the arrows;

Fig. 8 is a sectional view taken upon the line 8—8 of Fig. 1 looking in the direction of the arrows;

Fig. 9 is a detail plan of Fig. 8;

Fig. 10 is a sectional view taken upon the line 10—10 of Fig. 9;

Fig. 11 is a sectional view taken upon the line 10 11—11 of Fig. 7; and

Fig. 12 is a diagrammatic view of the wiring diagram.

Like reference characters designate like parts in the drawings and in the description thereof following hereafter.

Before proceeding with the detailed description of the construction and operation of the several parts comprising the embodiment shown in the drawings, and to better indicate the concepts of our invention, we describe in brief outline below the organization and coaction of the principal sub-combinations and parts comprising said embodiment. More particularly, our improved Braille writer is shown as including (1) a first 20 adapter unit which is actuated through movement of the keys of an ordinary typewriter, (2) a second adapter unit which is controlled by the first described unit and which in turn actuates the embossing rods of a Braille typewriter and (3) an electrical control circuit including switch elements which (a) in one position enable the operator to form Braille characters which correspond to the ordinary alphabet found on the conventional typewriter, and which (b) in a second position enable the operator to form additional characters which are included in the Braille alphabet but which are not included in the 26 letters in the ordinary alphabet.

Referring now in detail to the drawings, there 40 is shown a Braille writer 1 overlying a Braille writer actuating unit 3. The unit 3 is connected by a cable 11 to an adaptor unit 9 which is positioned beneath a typewriter 10. The electrical conductors of the cable 11 are in circuits controlled by switches closed by the typewriter key levers in a manner which will now be explained.

The illustrated typewriter comprises the keys 12 which are integral with key levers 13 fulcrummed at 14 and connected by links 15, levers 16 and links 17 to swinging type bars 18 as is well known in the art. A series of six parallel-spaced encoded bars 1, 2, 3, 4, 5 and 6, each with rabbeted ends 19, are positioned transversely below the key levers 13. These bars are mounted 50 in the adaptor unit 9, which is provided with a

cover 20 through which the upper portions of the bars project. The box has a bottom 23 and transverse end walls 24 which are provided with vertical guide slots shown as flat grooves 25 (Fig. 4). These guide grooves 25 are suitably spaced and of sufficient vertical extension to allow the encoded bars therein to descend into and remain in direct engagement with the upwardly spring pressed pins 26 of Microswitches 27 resting upon the bottom of the box. There is a Microswitch 27 at each end of each encoded bar. When referring to Microswitches we mean the precision snap switches sold under that trademark. We mean particularly those equipped with a longitudinally—here vertically—shiftable pin 26, biased toward one side—here upwardly—by suitable well known spring means, not shown herein. These spring means are used herein not only to provide a normal (open) position of the switches but also directly to support the encoded bars. Bracket members 28 extend from each of the end members 24, and are adapted to extend over the side walls of the typewriter 10 for attachment thereto. Set of screws 22 are provided to secure the adaptor unit 9 in place.

Thus, each encoded bar is guided by the slots in the cover and by the end grooves 25 in the end wall members 24 and is adapted for closing a switch at either end depending on whether it is depressed by a type lever adjacent either end.

Arms 28 extend from the adaptor unit 9 and are at suitable elevations to support Microswitches 29 which are adapted to be actuated by shift levers having keys 30 and 31 (Fig. 1). It will be understood that when the key levers depress the spring pressed pins 26, the springs will return the levers when the same are released. Attention, however, is directed to the fact that the key shift levers 30 and 31 merely actuate the switches 29 on the arms 28.

A third arm 96 extends from the adaptor unit 9 and provides support for a Microswitch 97, which is actuated by the space bar 98 of the typewriter 10.

In referring now to Fig. 5, which shows the six encoded bars in diagrammatic form, it will be noted that each is provided along its upper edge portion with rectangular notches. For example, the bar 1 is provided with notches 1a; the bar 2 is provided with notches 2a, and so on. These notches may be termed key avoiding notches in that when a key lever is depressed, it will not actuate those encoded bars having a notch directly thereunder. Thus the key lever marked Q will actuate encoded bars 1, 2, 3, 4 and 5, but not bar 6. Key lever A will actuate only encoded bar 1 since each of the other bars has a notch directly under such lever. Thus one or more encoded bars can be simultaneously actuated and the circuits controlled thereby closed.

Referring now to Fig. 7, there is shown a frame generally denoted by the reference 32 having ball bearings 33 for supporting a carriage 55 for travelling movements. A paper holding scroll 34 is mounted in the carriage 55 and the paper or work sheet is led over the paper feed roll 35 and under a spring presser 36 to the anvil 37 on a frame member 38. Beneath the anvil 37, there is a slotted head 39 on the vertical frame member 40. Six Braille embossing rods 41a, 41b, 41c, 41d, 41e, and 41f are slidably mounted in the slotted head 39 for embossing dots in the work sheet against the anvil 37. These rods 41a-41f are pivoted at their lower ends to levers 42a-42f which are pivoted intermediate their ends upon

pins 43 extending from the frame member 40. The other ends of the levers 42a-42f are pivotally connected to links 44a-44f, respectively, which in turn are connected to levers 45 pivoted at 46 and connected to key levers 47 having upturned ends 48 with keys 49. But the levers 47 are not usually operated by the keys 49, but by solenoids as will now appear.

Each lever 47 is connected by a link 50 which in turn is connected at its lower end to a solenoid operated lever 51. The solenoid lever 51 is pivoted at its remote end to a support 52 and at an intermediate point to the armature 53 of a solenoid 54. Energization of the solenoid 54 will draw the armature 53 downwardly and move lever 45 so as to force the appropriate lever 42 to elevate its embossing rod 41 which is connected thereto. Fig. 7 merely shows three embossing rods, but it will be understood that there are six which are all operated by solenoids as just explained.

During the operation of the Braille writer 7, the carriage 55 may be spaced and the paper feed roll 35 advanced by any suitable typewriter mechanism. In the embodiment of the drawing this mechanism comprises a motor 56 which is geared to a shaft 57 journalled in a standard 58. A gear 59 is secured to the shaft 57 between the motor and standard and this gear 59 meshes with a gear 60 on a stub shaft 61 supported by the standard 58. The gear 60 meshes with a gear 62 secured to a shaft 63 journalled in the standard 58 and extending therethrough and fixedly carrying a ribbon reel 64 upon which a ribbon 65, connected at one end to the carriage 55, is adapted to be wound. The gearing described constitutes a reduction gearing that will reduce the speed of the motor 56. Thus operation of the motor will rotate the reel 64 and wind up the carriage return ribbon 65. To stop the motor 56 at the proper time when the carriage has been returned, there is provided the following mechanism:

The shaft 57 extends through the standard 58 and carries a gear 66 fast thereon, which gear meshes with a gear 67 fast upon a shaft 68 journalled in standard 58 and a similar standard 69 which also supports one end of the reel shaft 63. A small gear 70 is secured to shaft 68 in spaced relation to gear 67 and this gear 70 meshes with a larger gear 71 secured to a shaft 72 journalled in standard 69 and extending therethrough and fixedly carrying a cam 73 having a rise 74 adapted for opening a Microswitch 75 in the motor circuit and stopping the motor 56. The gearing between the motor 56 and the cam 73 is designed to cut out the motor when the carriage 55 has been returned.

In Figs. 8 and 9 there is shown mechanism for rotating the paper feed roll 35 to advance the paper in line spacing direction. The roll 35 is secured to a shaft 76 projecting through a support 77 carried by the carriage. An indexing cam 78 is secured to the shaft 76 between the end of the roll and the casing. This cam has equally spaced depressions or dwells 79 into which a conventional spring loaded retainer (not shown) is adapted to snap as the paper roll 35 is rotated. A knob 80 is secured to the end of the roll shaft 76 for rotating the paper feed roll 35 manually if occasion requires.

The paper feed roll 35 is designed to be automatically advanced each time the carriage 55 is moved to starting position. To this end, a ratchet 81 is secured upon the roll shaft 76 for engagement by a pawl 82 pivoted to a lever 83 journalled upon the shaft 76 as an axis. The plunger 84 of

the solenoid 85 is connected to the pawl 82 through the link 86. As best shown in Fig. 10, the solenoid 85 is fastened to the support 77 by means of the clamp lip 87 and the fasteners 88. By means of the carriage return and line spacing apparatus thus described, the Braille writer 7 may be operated remotely. However, when the operator desires to use the Braille writer independently, the lever 89, which pivots on the pin 90 and is connected to the lever 83 through the link 91, may be used to return the carriage and advance the roll 35.

Referring now to Fig. 7, the Braille writer actuating unit 8 is provided with pivoted key levers 92 which are positioned for engaging push pins 94 of Microswitches 95. A space bar 93 is also provided, and actuates the Microswitch 105. Through the action of the Microswitches 95, as will later appear in the wiring diagram, the operator may control the solenoids 54. The switches 95 are normally open, however, and do not interfere with the use of the typewriter 10 as the primary actuating means.

Referring now to Fig. 12 which illustrates somewhat schematically the electrical control circuit of our invention, the Microswitches 27 operated by the encoded bars 1 to 6 are here designated as 1, 2, 3, 4, 5 and 6 to correspond with said bars, and these switches are normally open. It will be noted that only one switch 1, 2, etc. is shown for each of the six bars 1, 2, etc.; in other words, the two Microswitches at the two ends of each bar are connected in parallel, so that it is a matter of indifference whether a bar 1, 2, etc. is depressed adjacent either end or in the middle. The switches 29, 29 operated by the shift bars 30 and 31 constitute two switches which are connected in parallel and control a reverse switch solenoid 99. Still referring to the electrical components associated with the typewriter adaptor unit 9, there is included a spacing switch 97, which is actuated by the space bar 98, and a motor and carriage return switch 100, which is secured to the typewriter 10 by the bracket 101 (Fig. 2). The circuit of the typewriter adaptor unit 9 is also provided with a plurality of switches 1a, 2a, 3a, 4a, 5a and 6a which are moved as a unit by the reverse switch solenoid 99. As will be apparent upon inspection of Fig. 12, when the switches 1a-6a are in the position shown, the circuits of the switches 1-6 are connected to the correspondingly numbered terminals of the female socket 102. However, when the switches 1a-6a are moved downwardly to engage the alternate contacts, the switches 1, 2, 3, 4, 5 and 6 are connected to the terminals 4, 5, 6, 1, 2 and 3 of the socket 102, in that order. The manner in which this alternate alignment of the switches 1a-6a is used in our invention, will become more apparent as this exposition proceeds.

The socket 102 is connected to a similar socket 103 through the plugs 104 and 105 of the cable 11. As long as the switches 1a-6a are in the position shown in Fig. 12, the circuits including switches 1-6 are in series with the solenoids 54-1 to 54-6, inclusive. The circuit including the spacing switch 97 is also in series with the solenoid 108. The motor and carriage return switch 100 is likewise in series with both the motor 54 and the solenoid 85 (Fig. 8). Accordingly, whenever one or a combination of the switches 1-6 is closed (the circuit being arranged as shown), the corresponding solenoids 54-1 to 54-6 are energized and their associated embossing rods 41a-41f are actuated to imprint upon

the paper in the Braille writer 7. It will also be apparent that if desired the operator may through actuation of the keys 92 and 93 of the Braille writer 7 (Fig. 7), control the solenoids 54-1 to 54-6 and the solenoid 108, to actuate the embossing rods 41a-41f independently of the typewriter 10.

Advantageously, the use of the reverse shift solenoid 99 enables the user of the typewriter 10 to generate an entire series of Braille characters which do not correspond to any of the 26 letters found in the ordinary alphabet. We have found, for example, that a considerable number of these additional characters, which are in fact shorthand symbols to expedite writing by the blind, are formed by merely changing the order in which the switches 1-6 actuate the solenoids 54-1 to 54-6, as indicated above. For example, when the key 12 for the letter Y is depressed, while the switches 1-6 are in the position shown in Fig. 12, the encoding bars 1, 3, 4, 5 and 6 are depressed (Fig. 5), and the embossing rods 41a, 41c, 41d, 41e and 41f emboss the Braille symbol for Y on the paper in the Braille writer 7. Now, if the operator presses one of the reverse keys 31 before depressing the key 12 normally marked Y, the shift solenoid 99 changes the circuit so that the rods 41d, 41a, 41b and 41c are actuated. This embosses a symbol which in Braille denotes the word "and." In the same manner the Braille shorthand word and letter characters indicated at the bottom of Fig. 5, may be reproduced by the Braille writer 7.

While the keyboard shown in Fig. 6 would be confusing to a person with sight, the average blind person can quickly learn to visualize where each shorthand symbol is located. This is particularly so since the two symbols on each key are the same except that the two vertical rows of dots are interreversed. Thus there is a direct relationship between each pair of symbols. After the blind person has memorized the keyboard of Fig. 6, then he is able to type at a much faster rate and with less effort than is possible were he to use a standard Braille writer.

Having thus disclosed the nature of our improved Braille writing apparatus and demonstrated its utility by reference to a specific embodiment thereof, we claim as our invention:

1. In an apparatus of the class described, a plurality of encoded, substantially horizontal bars extending along one another and having upper edges with notches, a plurality of finger-operated levers extending over and across said notched edges and adapted for engaging unnotched portions of such bars, a plurality of parallel-connected switches having vertically movable, upwardly biased actuators distributed along each bar and supporting the same for actuation thereby, electric power means in series with the parallel-connected switches of each bar, Braille character forming members, and means for connecting said power means and members.

2. In an apparatus of the class described, a plurality of encoded straight, substantially horizontal bars having upper edges with notches, a plurality of finger-operated levers extending over and across said notched edges and adapted for engaging unnotched portions of such bars, a pair of parallel-connected switches having vertically movable, upwardly biased actuators supporting the ends of each bar for actuation thereby, a solenoid in circuit with each pair of switches, Braille character-forming members, and means connecting said solenoids and members.

3. In an apparatus of the class described, a plurality of Braille embossing members for embossing dots in a sheet of paper or the like, a plurality of solenoids, one operatively connected to each member, a circuit for each of said solenoids, a plurality of operating switches, means for selectively closing said operating switches, a gang switch interconnecting said operating switches and said solenoid circuits, said gang switch in different positions interconnecting said operating switches with different solenoid circuits, and means for moving said gang switch to different positions.

4. Apparatus of the class described in claim 3, in which said means for closing said operating switches comprises a plurality of encoded bars each positioned to close a different one of said switches upon being moved downwardly, said encoded bars each having a plurality of notches in the upper edge thereof, and a plurality of finger operated levers positioned above said encoded bars for engaging unnotched portions of said bars.

5. Apparatus of the class described in claim 3, in which said means for moving said gang switch to different positions comprises a solenoid operatively connected to said gang switch, a normally open switch in series with said solenoid, and a finger operated key for closing said solenoid switch.

6. In an apparatus of the class described, a plurality of Braille embossing members for embossing dots in a sheet of paper or the like in two parallel rows, a plurality of solenoids, one operatively connected to each member, a circuit for each of said solenoids, a plurality of operating, but normally open switches, a gang switch interconnecting said solenoid circuits and said operating switches, said gang switch in a first position connecting half of the operating switches to the solenoids for making one row of dots and the other half of the operating switches to the solenoids for making the second row of dots, said gang switch in a second position interchanging the connections between said operating switches and said solenoids for making each row of dots, and means for changing the position of said gang switch, and finger operated levers for simultaneously closing one or more of said operating switches.

7. In an apparatus of the class described, a plurality of finger operated levers, six encoded bars beneath said levers and extending transversely thereof in spaced relation, said bars each having notches in its upper edge for avoiding engagement by certain levers, a switch for and

5 actuated by each encoded bar to close upon downward movement of said bar, six solenoids and six Braille embossing members each actuated by a different one of said solenoids, said embossing members positioned to emboss dots in paper or the like in two vertical parallel rows of three dots each, a circuit for each of said solenoids, a gang switch one side of which is connected to said bar actuated switches, the other side of said gang switch being connected to said circuits of said solenoids so that alternate positions of said gang switch connect said bar actuated switches to said solenoids for actuating embossing members in different rows but in the same relative position within each row, and means for positioning said gang switch in either one of said alternate positions.

8. Apparatus of the type defined in claim 7, in which said gang switch positioning means comprises a solenoid mechanically coupled to said switch, a circuit for said solenoid, and a key operated switch in said circuit for selectively energizing said solenoid.

9. In an apparatus of the class described, a plurality of finger operated levers, a plurality of encoded bars beneath said levers and extending transversely thereof in spaced relation, said bars each having notches in their upper edges for avoiding engagement by certain levers, a switch positioned beneath each encoded bar to close upon downward movement of said bar, a plurality of solenoids equal in number to said bars, a plurality of Braille embossing members each actuated by a different one of said solenoids, a circuit for each of said solenoids, a gang switch one side of which is connected to said switches beneath said encoded bars, the other side of said gang switch being connected to said circuits of said solenoids so that alternate positions of said gang switch connect said bar actuated switches to different solenoid circuits, and means for positioning said gang switch in either one of said alternate positions.
